CLAIM

The ornamental design for a combined cigarette and lighter case, as shown in the drawings.

DESCRIPTION

FIG. 1 is a perspective view of a combined cigarette and lighter case showing my new design.

FIG. 2 is a front plan view of the combined cigarette and lighter case shown in FIG. 1.

FIG. 3 is a rear view of the combined cigarette and lighter case shown in FIG. 1.

FIG. 4 is a side view of the combined cigarette and lighter case shown in FIG. 1.

FIG. 5 is a side view of the combined cigarette and lighter case, similar to the view shown in FIG. 4, but with a pivotable cover for the case shown in an open position; and, FIG. 6 is a perspective view of the combined cigarette and lighter case, similar to the view shown in FIG. 1, but with the pivotable cover for the case shown in the open position.
